UNITED STATES PATENT OFFICE.

CLARENCE D. MILLER, PERRY D. MILLER, AND JOHN O. GADBERRY, OF CARTHAGE, MISSOURI.

SPRING-BED CONSTRUCTION.

1,139,050.

Specification of Letters Patent.

Patented May 11, 1915.

Application filed January 15, 1914. Serial No. 812,300.

To all whom it may concern:

Be it known that we, CLARENCE D. MILLER, PERRY D. MILLER, and JOHN O. GADBERRY, citizens of the United States, residing at Carthage, in the county of Jasper and State of Missouri, have invented a new and useful Spring-Bed Construction, of which the following is a specification.

The device forming the subject matter of this application is a spring bed construction, and one object of the invention is to provide a device of this type which will present a flush upper surface.

Another object of the invention is to provide novel means for connecting the springs with each other, with the ties and with the frame portions of the bed.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:—Figure 1 shows in top plan, a portion of a spring bed constructed in accordance with the present invention, parts being broken away; Fig. 2 is a section on the line 2—2 of Fig. 1; Fig. 3 is a section on the line 3—3 of Fig. 1; Fig. 4 is a perspective view showing the upper portions of the springs and the ties; Fig. 5 is a perspective showing the manner in which the lower portions of the springs are assembled with the intersecting ties at the bottom of the bed; Fig. 6 is a detail perspective view illustrating a modification of that portion of the structure depicted in Fig. 5.

In carrying out the present invention there is provided a top frame 1 and a bottom frame 2 of any desired construction, opposed portions of the top frame 1 being connected by longitudinally extended stays, preferably in the form of wires 3 having upstanding bends 4 at intervals therein.

A plurality of helical springs are provided. The springs preferably are of spiral form, as shown in the drawings. The upper convolutions of each spring are denoted by the numeral 5 and in the upper convolution

6 passes across the top of the stay 3 and the bend 4 in the stay 3 is disposed between the side portions of the loop 6. In the upper convolution 5 of each spring, opposite to the loop 6 there is formed a depending bend 7. The free end of the upper convolution of each spring is formed into a radially extended tongue 8. The tongue 8 passes beneath the bend 4 of the stay 3 and is bent upwardly as indicated at 9 to pass across the end of the loop 6, the tongue 8 terminating in a hoop 10 which is engaged in the bend 7 of the next spring.

Comparing Fig. 4 with Fig. 1 and noting the second row of springs from the side portion of the frame 1 it will be observed that the bend 4^a of the stay and the bend 7^a of the spring are disposed in adjacent and in overlapped relation. In the case of the outermost row of springs, the loop 6^a is disposed adjacent the frame 1 and the hook 10^a, corresponding to the hook 10, is engaged around the frame 1 and around the end of the loop 6^a. The bends 7^b of the outermost row of springs are disposed toward the 80 bends 7^a of the second row of springs as will be understood from Figs. 1 and 2 and a link 11 is provided for connecting these bends, the link 11 terminating at one end in an eye 12 which engages the bend 7^b and terminating at its other end in an S-shaped hook 14 which passes around the bend 7^a in the spring and around the bend 4^a in the stay.

Opposed portions of the bottom frame of the bed are united by intersecting stays 15 and 16. The stay 15 is bent upwardly as shown at 17 and the stay 16 is bent upwardly as shown at 18, thus to form shoulders 19 in the stay 15 and to form shoulders 20 in the tie 16. The lowermost convolution 21 of the 95 spring passes inside of the shoulders 19 and outside of the shoulders 20 and terminates in a depending finger 22 engaging the stay 16 close to one shoulder 20 as shown in Fig. 5.

The construction shown in Fig. 5 may be modified to the extent indicated in Fig. 6, wherein the intersecting stays at the bottom of the bed are denoted by the numerals 23 and 24, the stay 23 being bent upward as 105 at 25 to form shoulders 26 and the stay 24 having an upward bend 27 of less extent than the bend 25. The lowermost convolution of the spring is indicated at 28 and passes inside of the shoulders 26, in contact 110

therewith. The extremity of the convolution 28 terminates in an arm 29 disposed approximately parallel to the stay 23 and terminates in a depending finger 30 engaging 5 the stay 24 in abutment with the bend 27.

5 The spring bed herein disclosed will be found peculiarly efficient in that it presents a flush upper surface and that the springs of the bed are assembled firmly with 10 each other and with the stays.

Having thus described the invention, what is claimed is:—

1. In a spring bed, a stay wire; a spring the terminal convolution of which is provided with a bend, and with a lateral loop disposed opposite to the bend and extending across the stay, the end of the terminal convolution being formed into an outstanding tongue which passes across the stay and 15 across the end of the loop, the end of the tongue being connected with the first specified bend of an adjoining spring, the stay and the bend engaging opposed edges of the tongue.

20 2. In a spring bed, a stay wire having a bend; a spring the terminal convolution of which is provided with a bend and with a lateral loop disposed opposite to the bend

and extended across the stay, the bend in the stay lying between the side portions of 30 the loop, the end of the terminal convolution being formed into a tongue extended across the bend of the stay and across the end of the loop and passed between the bend of the stay and the end of the loop, the end of the tongue being connected with the first specified bend of the adjoining spring.

25 3. In a spring bed, a stay having a bend; a spring, one convolution of which is provided with a lateral loop, the bend in the stay 40 lying between the side portions of the loop, the end of the said convolution of the spring being extended across the side of the loop and bent within the contour of the loop to form into a tongue which is extended beneath the bend of the stay and across the end of the loop in the spring.

In testimony that we claim the foregoing as our own, we have hereto affixed our signatures in the presence of two witnesses.

CLARENCE D. MILLER.
